UNITED STATES PATENT OFFICE.

SOLOMON M. MEYENBERG AND ROBERT COLLINGE, OF PATERSON, N. J.

DESIGN FOR VEILS.

Specification forming part of Design No. **6,870**, dated September 2, 1873; application filed July 5, 1873.
[Term of Patent 3½ years]

To all whom it may concern:

Be it known that we, SOLOMON M. MEYENBERG, of Paterson, Passaic county, New Jersey, and ROBERT COLLINGE, of the same place, have invented a Design for a Veil, of which the following is a specification:

The nature of our design is fully represented in the accompanying drawing, to which reference is made.

A represents the body of the veil, preferably of fringe-silk, and with or without an ornamental border. B is the fringe of the veil formed of the silk threads of body A, which project at suitable length beyond the same. Along the whole outer edge of body A suitable numbers of adjoining silk threads are gathered and formed into knots. One-half of the threads of one knot are again tied with about one-half of those of the adjoining knot, so that a border-fringe with two rows of knots and tassel-shaped ends is obtained.

Additional rows of knots may be produced by continuing to tie one-half of the threads of the tassel-shaped portion with the same part of the adjoining portion, so that different configurations of the border-fringe are formed by the silk threads, which make up and extend from the body of the veil. The knots may also be left off entirely, and the fringe be produced only by the projecting ends of the threads.

What we claim as our invention is—

The design for a veil, as described and shown.

SOLOMON M. MEYENBERG.
ROBERT COLLINGE.
